SMOKER'S PIPE OR SIMILAR ARTICLE

Philip D. Berenson, Elizabeth, N.J. (44 Montgomery St., Jersey City 2, N.J.), assignor of one-half to Weber Briars, Inc., Jersey City, N.J., a corporation of New Jersey

Filed Oct. 23, 1963, Ser. No. 77,106

Term of patent 7 years

(Cl. D85—8)

FIG. 1 is a plan view of a smoker's pipe, or similar article showing my new design; the bowl being omitted from this view for convenience of illustration; and

FIG. 2 is a front elevational view thereof, partly in section taken on the line 2—2 of FIG. 1.

The dominant features of my design reside in the parts shown in solid lines in the drawing.

I claim:

The ornamental design for a smoker's pipe or similar article, substantially as shown and described.
